Primary Examiner — Marissa J Cash*Assistant Examiner* — William B Melliar(74) *Attorney, Agent, or Firm* — Middleton Reutlinger(57) **CLAIM**

The ornamental design for the security light, as shown and described.

DESCRIPTION

FIG. 1 is a lower perspective view of a security light showing the new design;

FIG. 2 is a rear perspective view of the security light design of FIG. 1;

FIG. 3 is a front view of the security light design of FIG. 1;

FIG. 4 is a rear view of the security light design of FIG. 1;

FIG. 5 is a top view of the security light design of FIG. 1;

FIG. 6 is a bottom view of the security light design of FIG. 1;

FIG. 7 is a left side view of the security light design of FIG. 1; and,

FIG. 8 is a right side view of the security light design of FIG. 1.

The broken lines shown in the drawings depict portions of the security light that form no part of the claimed design.

1 Claim, 8 Drawing Sheets(56)
